DESIGN FOR A LUBRICATOR CASING

Dugald A. Shaw, Canton, Ohio, assignor to The
United States Air Compressor Company

Application March 31, 1939, Serial No. 83,946

Term of patent 14 years

To all whom it may concern:

Be it known that I, Dugald A. Shaw, a citizen of the United States, residing at 1108 North Market Avenue, Canton, Ohio, in the city of Canton, county of Stark, and State of Ohio, have invented a new, original, and ornamental Design for a Lubricator Casing, of which the following is a specification, reference being had to the accompanying drawing, constituting a part thereof;

Figure 1 is a perspective view of a lubricator casing showing my new design;

Figure 2 is a front elevational view of the lubricator casing shown in Figure 1; and

Figure 3 is a rear elevational view of the lubricator casing shown in Figure 1.

I claim:

The ornamental design for a lubricator casing, substantially as shown.

DUGALD A. SHAW.
